UNITED STATES PATENT OFFICE

CHARLES MILLER, OF NEW YORK, N. Y.

DESIGN FOR A SHOE

Application filed July 22, 1932. Serial No. 44,417. Term of patent 3½ years.

To all whom it may concern:

Be it known that I, CHARLES MILLER, a citizen of the United States, residing at New York, in the county of New York and State of New York, have invented a new, original, and ornamental Design for Shoe, of which the following is a specification, reference being had to the accompanying drawing, forming part thereof.

I claim:

The ornamental design for a shoe, as shown.

CHARLES MILLER.
